CLAIM

The ornamental design for a hair dryer, as shown and
described.

DESCRIPTION

1. Hair dryer
- 1.1 : Left
- 1.2 : Right
- 1.3 : Top
- 1.4 : Bottom
- 1.5 : Back
- 1.6 : Front
- 1.7 : Perspective

(Continued)

The design consists of the features of shape and configuration of a hair dryer as shown in solid lines in the drawings.
